UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

Application filed September 25, 1919. Serial No. 326,136.

To all whom it may concern:

Be it known that I, REUBEN B. BENJAMIN, a citizen of the United States, residing at Chicago, in the county of Cook and State 5 of Illinois, have invented new and useful Improvements in Electric Switches, of which the following is a full, clear, concise, and exact description, reference being had to the accompanying drawing, forming a 10 part of this specification.

My invention relates to electric switches.

One of the objects of my invention is to provide an improved switch in which two breaks are made in the circuit substantially 15 simultaneously, thus dividing and decreasing the arcing effect, and consequently lessening the danger of injury to the switch and other undesirable effects.

A further object of my invention is to 20 provide an electric switch for use in an electrical receptacle, which will be simple in construction, durable and efficient in use, and cheap to manufacture.

Further objects will appear from the detailed description to follow and from the appended claims.

In the drawings, in which two embodiments of my invention are shown:

Fig. 1 is a plan view of a pull switch 30 socket embodying my invention;

Fig. 2 is a section substantially on the line 2—2 of Fig. 1;

Fig. 3 is a section substantially on the line 3—3 of Fig. 1;

Fig. 4 is a section substantially on the line 4—4 of Fig. 3;

Fig. 5 is a section substantially on the line 5—5 of Fig. 3;

Fig. 6 is a section substantially on the line 2—2 of Fig. 1 showing the parts in a different position;

Fig. 7 is a section substantially on the line 7—7 of Fig. 3;

Fig. 8 is a detail perspective view of the combined chain hook and pawl member;

Fig. 9 is a detail perspective view of an electrical connecting member; and

Fig. 10 is a perspective view of one of the rotating contacts.

In order to give a general idea of the construction, it is here stated that my invention is here shown embodied in a pull switch socket, having shell and center contacts 15

and 16 respectively, for engagement with an insertible device of the Edison type, and having wiring terminals 17 and 18 for connection with a pair of feed wires, (one of the wiring terminals 17 being directly connected with the threaded shell contact of the receptacle) and a pull switch mechanism 60 having two rotatably mounted contacts 19 and 20 (insulated from each other in the "off" position of the switch) one of these contacts 19 being electrically connected with the center contact 16, and the other rotatable contact 20 being electrically connected with the other wiring terminal 18, and a relatively stationary electrical conducting member 21 with which the two rotatable contacts 19 and 20 both make electrical contact in 70 their movement, and with respect to which both of said rotatable contacts are movable out of contact in their movement, whereby as the rotatable contacts are rotated, the circuit from the wiring terminal to the center contact is broken at two points, substantially simultaneously. The receptacle contacts, switch mechanism and wiring terminals are all mounted on an insulating base 22 and this insulating base and parts carried 75 thereby are housed in a sheet metal casing 23, having a sheet metal cap 24 which can be removed for wiring, repair, etc. The usual lining 25 of insulating material, such as fibre or the like, is provided between the 80 shell contact 15 and the casing 23, and a cover 26 of suitable insulating material, of fibre, is provided above the insulating base 22 to prevent short circuiting of the live parts carried by the insulating base. 90

The wiring terminal 17 is electrically connected with the threaded shell contact 15 by means of a screw 27 (Figs. 1 and 4) the head of which engages the flange 28 of the threaded shell contact, and the upper end 95 of which is threaded into the wiring terminal 17. The wiring terminal 18 is secured on the insulating base 22 by means of a screw 29 (Fig. 1) the wiring terminals 17 and 18 are provided with the usual binding 100 screws 29.

The pull switch mechanism comprises (in addition to the two separated rotatably mounted contacts 19 and 20 and the connecting member 21, previously referred to) 105 a rotatably mounted insulating contact car-

rier 30 (which may be of molded material) the contact carrier together with the contacts carried thereby forming a commutator member, an operating pawl member 31, 5 (shown in perspective in Fig. 8) for imparting a step-by-step movement to the contact carrier and contacts, a pull chain 32 connected to the oscillating pawl member 31 to operate it in one direction, and a coil torsion spring 33 also connected to the oscillating pawl member 31 for returning it after it has been operated by the pull chain 32. The central portion of the contact carrier provides a support for the torsion spring 33, 10 the operating pawl 31, and the pull chain 32. The main body of the torsion spring 33 surrounds the central portion of the contact carrier. One end of the torsion spring is secured to a recess 34 in the insulating base 21 (Figs. 2, 3 and 6). The pull chain 32 is also secured to the operating pawl 31, this operating pawl being provided with two hook fingers 36, the end ball of the chain 32 being held in these hook fingers, and the 15 chain connecting this ball with the preceding ball extending between the hook fingers 36. The operating pawl 31 is provided with two outwardly and laterally extending fingers or lugs 37, which extend over for engagement with two ratchet portions 38 of the contact carrier, the laterally extending portions of these fingers riding upon the narrow periphery of the ratchet portions 38, 20 during the relative movement of the operating pawl with respect to these ratchet portions, and slipping down in behind the shoulders 39 in position to engage the shoulders when the pawl is operated by pulling 25 down the pull chain 32.

40 This pull chain 32, as previously stated, is secured to the hook portions 36, and overlies the body portion of the operating pawl, and extends between the outwardly and laterally extending hook fingers 37.

45 The portion of the contact carrier 30 between the ratchet portion 38 constitutes a support for the torsion spring 33, and indirectly for the operating pawl 31 and pull chain 32, the pull chain 32 bearing on the 50 torsion spring and also on the operating pawl, and the operating pawl being supported by the spring. When the pull chain 32 is pulled it bears down on the operating member 31 to insure that the laterally extending fingers 37 stay in engagement with the shoulders 39 of the ratchet portions 38. To one end of the contact carrier 30 is secured a shaft 40 (this shaft may be molded in place) the end of which is mounted in 55 a bearing portion 41, formed integral with the binding plate of the wiring terminal 18. The contact 20 is electrically connected with this wiring terminal 18 by means of an inwardly extending arm 42 formed integral 60 with the contact, this arm 42 having an

opening 43 to which said shaft 40 extends, the arm 42 serving not only to electrically connect the contact with the bracket portion 41 but also to hold the contact in place on the contact carrier. 70

The other end of the contact carrier is provided with a shaft 44 (which may be molded in place in the brush carrier). The outer end of said shaft 44 is mounted in an opening in a spring bracket 45, which spring bracket 45 is secured in place on the insulating base 22 by means of a screw 46, which also serves to electrically connect the bracket 45 with the center contact 15 and also serves to hold the center contact 16 in place on the insulating base. The contact 19 is provided with an inwardly extending arm portion 47, having an opening through which said shaft 44 projects (Fig. 5) the arm portion 47 serving to hold the contact 19 in place on the contact carrier and also to electrically connect the contact with the bracket 45. The contact 19 is thus electrically connected with the center contact 16 through the arm portion 47, the bracket 45 and the 80 screw 46.

An electrical connecting member 21 with which the contacts 19 and 20 are alternately connected and disconnected comprises a face portion 48 (Figs. 2, 6 and 9) and two spring contact fingers 49 and 50 for cooperating with the contacts 19 and 20 respectively. 95

The operation of the device is as follows:

Assuming that the parts are in the position shown in Figs. 1, 2, 5 and 7 (which is the "on" position of the switch) and it is desired to turn the switch off, the chain 32 is pulled down swinging into the position shown in Fig. 6. This movement of the chain and pawl is limited by the fingers 37 of the pawl, swinging into contact with an abutment portion 51 on the insulating base 22. During this movement of 180 degrees, the contact carrier also is rotated through an angle of 180 degrees, by the engagement of the fingers 37 with the shoulder 39 of the ratchet portion 38 of the carrier. As the contacts are rotated through this angle of 180 degrees, the spring fingers 49 and 50 ride along the spiral contact portions of the contacts 19 and 20, and at the end of the movement snap off from the rear ends, of the contacts into engagement with the carrier itself. This breaks the circuit between the wiring terminal 18 and the center contact at two 110 points, thus dividing the arc and lessening the danger of harm resulting from arcing. 120

When the pull chain 32 is released, the torsion spring returns the operating pawl 31 and pull chain 32 to the position shown in Figs. 5 and 7. During this return movement of the operating pawl the fingers 37 ride upon the ratchet portion 38 of the carrier and finally drop off behind the shoulders 39, 125 in position to catch the carrier on the next 130

- downward movement of the pull chain. The carrier itself remains stationary during this return movement of the operating pawl and pull chain, as any tendency of the carrier to travel along with the operating pawl on this return movement would be prevented by the engagement of the ends of the spring tongues 49 and 50 with the shoulder portion 52 (Figs. 5 and 7) of the carrier.
- 10 The return movement of the operating pawl and pull chain is limited by the engagement of the hook fingers 36 with an abutment portion 53 formed integral with the insulating base 22 (Fig. 2).
- 15 If now with the parts in "off" position, it is desired to turn the switch "on", the chain 32 is again pulled, to move the operating pawl 31 to an angle of 180 degrees. During this movement 20 of the operating pawl 31, the contact carrier also is rotated through 180 degrees, by the engagement of the fingers 37 with the shoulders 39 of the ratchet portion 38 of the carrier. When the pull chain is released, the 25 operating pawl and pull chain are again returned by means of the spring 33, the fingers 37 again riding on the ratchet portion 38 of the carrier, and at the end of the return movement dropping down behind the shoulders 39 in position to again cause the movement of the carrier on the downward pull of the pull chain. During this movement of the carrier, the spring fingers 49 and 50 ride upon the spiral portions 54 of the carrier it- 30 self, and at the end of the movement snap down from these spiral portions 54 into engagement with the contacts 19 and 20 respectively, thus making the circuit simultaneously at two points. When the pull chain is re- 35 leased, the torsion spring 33 again returns the pull chain and operating pawl to the original position.
- Having thus described my invention, what I claim as new and desire to secure by Letters Patent is:
1. A switch comprising a pair of rotatable contacts; a flexible pull member for imparting movement to said contacts; and a coil torsion spring for returning said pull member; the coils of said torsion spring being located between said contacts and serving as a supporting drum for said pull member.
2. A switch comprising a rotatable one-piece contact carrier of insulating material; a pair of contacts carried thereby; means including a pull member for operating said carrier; and a coil torsion spring surrounding said carrier between said contacts for returning said pull member.
3. A switch comprising a rotatable contact carrier; a pair of contacts carried thereby; means including a pull member for operating said carrier; and a coil torsion spring surrounding said carrier between said contacts for returning said pull member, the coils of said torsion spring serving as a supporting drum for said pull member.
4. A switch comprising a rotatable contact carrier having a cylindrical portion, and a ratchet portion, a torsion spring surrounding said cylindrical portion and a pawl for engaging a ratchet portion of said carrier to rotate it, said pawl being secured to the spring at one end, and riding on said spring, and an operating chain for moving said pawl, said pawl being held in operative position by said chain.
5. A switch comprising a rotatable contact carrier; a contact carried thereby, said contact carrier having a flange portion terminating in a shoulder; a pawl for actuating said carrier, a chain for operating said pawl, said pawl having a portion which rides upon the periphery of said flange portion and moves down behind said shoulder, said flange constituting a barrier between said contact and said chain.
6. A switch comprising a rotatable contact carrier; a contact carried thereby, said contact carrier having a flange portion having a cam edge terminating in a shoulder; and a pawl for actuating said carrier having a laterally extending portion which rides upon said cam edge and moves down behind said shoulder, said flange constituting a barrier between said pawl and said contact.
7. A switch mechanism comprising a rotatable contact carrier; two spaced contacts carried thereby, said carrier having two spaced ratchet-shaped portions, each having a cam edge terminating in a shoulder; and a pawl for actuating said carrier located between said ratchet-shaped portions and having portions extending laterally in each direction for riding upon said cam edges and moving down behind said shoulders.
8. A switch mechanism comprising an integral contact carrier; two spaced contacts carried thereby; two spaced flanges located between said contacts; a pull member located between said flanges and retained in place thereby; and a coil torsion spring for returning said pull member after it has been actuated, said torsion spring being smaller in diameter than said flanges and being sprung into place over one of said flanges.
9. A switch mechanism comprising a one-piece insulating rotatable contact carrier; two contacts supported by said contact carrier, and rotatable in different parallel planes transverse to the axis of the carrier; an oscillatable pull member for operating said carrier; a ratchet connection between said oscillatable member and said carrier whereby oscillation of said operating member will cause intermittent rotation of said carrier; and a coil torsion spring for re-

- turning said oscillatable member, said coil torsion spring surrounding said carrier and being located between the planes of said contacts.
- 5 10. A switch mechanism comprising a rotatable contact carrier; two contacts carried thereby, and rotatable in different parallel planes transverse to the axis of said contact carrier; two spaced flanges located between 55
10 the planes of said contacts; a pull member located between said flanges and retained in place thereby; a coil torsion spring for returning said pull member surrounding said contact carrier and located between said 60
15 flanges, said spring being smaller in diameter than said collars.
11. A switch comprising a rotatable contact carrier of insulating material, said carrier having an integral portion of reduced 65
20 diameter; a contact carried by said carrier; means for operating said contact carrier; said means including a pull member and a coil torsion spring surrounding the reduced portion of said carrier for returning said 70
25 pull member, said pull member bearing on and being supported by said torsion spring; and means for transmitting motion from said pull member to said spring, said means comprising a pawl, and said pawl being attached at one of its ends to said spring and at its opposite end to the pull member. 75
- 30 12. A pull socket comprising an insulating base, a switch mechanism carried thereby, said switch mechanism comprising a rotatable contact carrier, a pair of contacts carried by said carrier, a bearing for each end of said carrier, one of said contacts being electrically connected to one of said bearings and the other contact being electrically 80
35 connected to the other bearing, receptacle contacts carried by said base, a wiring terminal electrically connected to one of said contacts, one of said bearings being electrically connected to the other receptacle 85
40 contact, a second binding terminal electrically connected to the other bearing, said contact carrier having a portion of reduced diameter between the contacts carried thereby, a torsion spring surrounding said reduced portion, a pawl riding on said spring, a flexible pull member attached to said pawl, and a spring contact member engaging both 90
45 50 of the rotatable contacts and electrically connecting the same when the switch is closed, said spring contact member being arranged to snap off both of said rotary contacts at the same time, and open the circuit at two points in series. 95
13. A pull socket mechanism comprising a rotatable contact carrier, two contacts supported by said carrier and rotatable in parallel planes, said carrier being formed of insulating material and having a portion of reduced diameter between the contacts, a pawl member arranged between said contacts, a flexible pull member secured to said pawl member and arranged to normally lie in the space between said contacts and surrounding said portion of reduced diameter, a bearing for said carrier electrically connected to one of said contacts, a wiring terminal electrically connected to said bearing, a second bearing electrically connected to the other contact, a receptacle contact electrically connected to said second bearing, a second receptacle contact, and a spring contact member having two fingers extending therefrom upon opposite sides of said pawl and said pull member into engagement with the rotatable contacts. 100
14. A switch socket comprising a rotatable contact carrier, two bearings for said carrier, a pair of contacts carried by said carrier, one of said contacts being electrically connected to one of said bearings, the other contact being electrically connected to the other bearing, means for electrically connecting said contacts with each other comprising a pair of spring fingers electrically connected with each other and arranged to engage said rotary contacts and to snap off said contacts simultaneously, thereby breaking the circuit at two points in series, said contact carrier having a portion of reduced diameter, flanges of insulating material on opposite sides of said portion of reduced diameter, and oscillating means supported by said carrier on said reduced portion between said insulating flanges for intermittently rotating said carrier. 105

In witness whereof, I have hereunto subscribed my name.

REUBEN B. BENJAMIN.
